INDICATOR LIGHT FOR HOBBLING MACHINES

William S. Brower, Muncie, Ind., assignor to Borg-Warner Corporation, Chicago, Ill., a corporation of Illinois

Application January 11, 1949, Serial No. 70,225

7 Claims. (Cl. 177—311)

1

This invention relates to hobbing machines and more particularly to a device for indicating whether or not the hob has been shifted with respect to the work piece at the end of a cycle of operation so as to present a different cutting surface to the next work piece in the following cycle of operation.

In high production, automatic hobbing machines one practice is to use a hob having a greater number of rows of cutting teeth than are employed in cutting any one gear. Then, as the hob is used and wears, between cycles of operation the hob is shifted axially, that is, transversely with respect to the work piece to present a less worn cutting surface to the next work piece and thereby to distribute the wear evenly over the hob. While this shifting may be performed manually by the hobbing machine operator, because of the desirability of efficiently utilizing the full working surface of the hob by uniformly distributing the wear over the hob and because of the difficulty of doing this manually, automatic means are preferably provided for shifting the hob at the end of each cycle of operation. It has been found in practice that while such automatic shifting means may be made to provide fairly consistent operation, it is desirable to provide also a positive indication to the operator that the hob has been shifted and that the machine is ready to be reloaded and to begin the next cycle of operation.

An object of the present invention is to provide a simple, efficient, and economical hob shift indicator arranged to provide a visual signal as to whether or not the hob has been shifted at the end of a cycle of operation.

In accordance with one embodiment of this invention as applied to an automatic hobbing machine incorporating means for shifting the hob axially at the end of a cycle of operation, a hob shift indicator is provided comprising a micro-switch and a cam for actuating the micro-switch, the cam being arranged to rotate with a lead screw utilized for shifting the hob. The cam is rotated only if the hob is shifted; consequently, the micro-switch which controls a pair of lamps of different colors is actuated only if the hob is shifted to light one of the lamps and to extinguish the other of the two lamps. Means are also provided for returning the cam to dwell position and for preventing accidental actuation of the micro-switch during the hobbing cycle.

Other objects and advantages of the present invention will be apparent from the following

2

detailed description taken in conjunction with the drawings wherein:

In the drawings:

Fig. 1 is a fragmentary end view, partly in section showing a hobbing machine having a hob shift indicator associated therewith in accordance with this invention;

Fig. 2 is a view of the portion of the hobbing machine shown in Fig. 1, taken from the right side thereof as viewed in Fig. 1; and

Fig. 3 is an enlarged sectional view taken along the line 3—3 of Fig. 1.

Referring now to the drawings and particularly to Figs. 1 and 2 thereof wherein to simplify description and to facilitate a rapid understanding of the invention only that portion of a conventional automatic gear hobbing machine is illustrated which is directly pertinent to the present invention, a hob 10 is shown fixed on a driving shaft 11 which is rotatably supported by suitable supporting means indicated at 12, which means are mounted on a carriage 13. Suitable gearing (not shown) is also keyed to the shaft 11 for rotating the hob 10 with respect to a work piece indicated generally at 15. The work piece 15 may comprise as shown a plurality of stacked, gear blanks.

It will be understood that in the course of operation of the hobbing machine the work piece is simultaneously rotated and advanced vertically, as viewed in Fig. 1, with respect to the hob 10, while the hob 10 is rotated rapidly about its axis in a fixed position. Thus only a very small portion of the cutting surface of the hob is utilized in cutting one group of gear blanks.

To distribute the wear uniformly over the surface of the hob it is necessary to shift the hob axially a short distance between cycles of operation. In order to permit this axial adjustment and to allow movement of the hob transversely with respect to the position of the work piece, the hob carriage 13 is slidably dovetailed into a bed 16 and is arranged to be moved with respect to the bed by a lead screw 17. The lead screw 17 is rotated a predetermined angular distance at the end of each cycle of operation of the hobbing machine so as to advance the hob transversely with respect to the plane of the work piece and thereby to present a less worn cutting surface to the work piece, thus distributing the wear evenly over the hob. A suitable mechanism for accomplishing this intermittent actuation of the lead screw is that illustrated in Figs. 1 and 2 and comprises a gear 18 keyed to the lead screw 17 adjacent its left end, as viewed in Fig. 2, and

meshing with an intermediate spur gear 19 fixed to freely rotatable shaft 20. The shaft 20 is rotated by a third gear 21 keyed thereto and meshing with a fourth gear 22 keyed to a shaft 23 which in turn is rotated by gear 24 through a clutch arrangement 25 of generally conventional design, driving a gear 26 keyed to the clutch shaft 27, the gear 26 meshing with the gear 22. The clutch 25 comprises an outer ring gear 28 meshing with a rack 29 which is reciprocated by a hydraulically energized plunger 31 operated through the control system of the hobbing machine at the end of each cycle of the hobbing operation. Inner cam member 32 of the clutch 25 is keyed to the shaft 27 and comprises an octagonal disc and a plurality of roller pins 33 are disposed between the periphery of the disc 32 and the inner wall of the ring gear 28 so that when the hydraulic plunger 31 is actuated to move the rack 29, the clutch 25 engages and through the above described train of gears 18, 19, 21, 22 and 24 the lead screw 17 is angularly displaced to advance the hob carriage 13 with respect to the bed 16. The structure and operation so far described is conventional and since it is not claimed as part of the present invention, no more detailed description thereof is believed warranted.

In accordance with the present invention in order to provide a positive indication that the hob has been shifted at the conclusion of a cycle of operation, an indicator mechanism designated generally at 35 is provided and is arranged to be operated through the rotation of the lead screw 17 at the end of a cycle of operation of the hobbing machine. The indicator mechanism is supported on a mounting plate 36 which is suitably secured to the left end of the bed 16 of the hobbing machine. In order to provide a visual signal to the operator, two lamps 37 and 38 are provided and may be mounted in a suitably conspicuous place on or adjacent the hobbing machine. The lamp 37 may be red and indicates when lighted that the hob has been shifted, whereas the lamp 38 may be white and indicates when lighted that the hob has not been shifted or that the machine is in cycle.

The control of the lighting of these lamps is effected through a micro-switch 39 mounted on the plate 36 and connected to the lamps by leads 41, 42, and 43, the lead 42 being common. The operation of the micro-switch is in turn controlled by rotation of a cam 45 which is frictionally supported on a stub-shaft 46 by a split bushing 47. The stub-shaft 46 is supported at its left end, as viewed in Fig. 2, in a sleeve bearing 48, fixed in a cup-shaped housing 49 which is mounted on the plate 36. The cam 45 is arranged to be rotated by the lead screw 17, the left end of which extends through aperture 50 formed in the plate 36 and is squared to engage a complementarily squared collar 51 provided at the right end of the shaft 46.

The micro-switch 39 is provided with a spring-pressed plunger 52, the tip of which bears against the periphery of the cam 45 and when the lamp 38 is lighted extends into a notch 53 formed in the cam 45. Rotation of the cam from this position pushes the plunger 52 back, as the tip of the plunger rides out of the notch 53; this causes the lamp 37 to be lit and the lamp 38 to be extinguished.

Since it is desired that the indicator be operated only at the conclusion of a cycle of operation, and also to prevent false operation of the

indicator such as might be occasioned by a slight movement of the lead screw 17 in the course of the hobbing cycle itself, this invention also includes means for preventing rotation of the cam 45 except at the termination of the hobbing cycle. This means comprises a plunger 54 which is adapted to be received in a V-shaped notch 55 formed in the periphery of the cam 45. In the embodiment illustrated the plunger 54 is actuated by a hydraulic mechanism indicated generally at 56 and including a hydraulic line 57 for retracting the plunger and a second hydraulic line 58 for advancing the plunger. However, it will be understood that any other type of means for advancing and retracting the plunger might well be substituted, such for example, as a solenoid. In the embodiment illustrated, during the operation of the hobbing machine pressure is supplied through the hydraulic line 58 to maintain the plunger 54 in the notch 55 in the cam 45, the pressure being supplied from suitable pressure control apparatus operating in timed relation to the operation of the hobbing machine, thus preventing rotation of the cam 45. Under these circumstances, the cam 45 because of the split bushing support 47 slips relatively to the shaft 46.

At the conclusion of a cycle of operation of the hobbing machine, pressure is removed from the hydraulic line 58 and supplied through the hydraulic line 57 to retract the plunger 54. The cam 45 is now free to rotate with the shaft 17, and if the shaft 17 is rotated at this time through the actuation of the hydraulic plunger 31 and the above described gear train to advance the hob, then the cam 45 will be rotated to move the micro-switch plunger 52 out of the notch 53 and thereby energize the lamp 37.

The cam 45 is permitted to rotate in either direction, in accordance with the direction of rotation of the lead screw 17, a distance limited by the length of the recess 60 formed in the periphery of the cam 45 opposite the position of the notch 55 and approximately 90° removed from the position of notch 53. A stop pin 61 extends across this recess, the pin 61 being carried by the cup-shaped housing 49 and the end plate 36, and when the micro-switch plunger 52 is in the notch 53, at which time the hydraulic plunger 54 is in the notch 55, the pin 61 is positioned substantially at the middle of the recess 60, that is midway between the ends thereof. When the cam 45 is rotated however by the turning of the lead screw 17 and the shaft 46, the rotation of the cam is stopped when the pin 61 engages either end of the recess 60. The length of the recess 60 is selected not only to permit a sufficient rotation of the cam 45 to actuate the micro-switch but also to limit the rotation of the cam to an amount from which the hydraulic plunger 54 by engaging one of the V-shaped sides of the notch 55 may return the cam 45 to starting position, that is to the position where the micro-switch plunger 52 is received in the notch 53. The degree of frictional engagement of the split bushing 47 is controlled by a radially disposed threaded member 62, which is threaded in the cam 45 and the inner end of which bears against a side of the split bushing 47. By threading the member 62 into or out of the cam 45 the frictional engagement may be increased or decreased as required.

In the event the hobbing machine has failed to advance the hob at the conclusion of a cycle of operation, means are provided in accordance with this invention whereby the operator may

manually position the carriage 13 and hob 10 as required. Referring to Figs. 2 and 3 it will be seen that the left end of stub shaft 46 is extended beyond the housing 49 and squared to provide a head 63 to which a crank, not shown, may readily be fitted by the operator. Rotation of the stub shaft 46 will cause rotation of the lead screw 17 and movement of the carriage 13.

Where herein the various parts of the hobbing machine of this invention have been referred to as being located in a right or a left position, it will be understood that this is done solely for the purpose of facilitating description and that the references relate only to the relative position of the parts as shown in the accompanying drawings.

What is claimed is:

1. In a hobbing machine, means for shifting the hob, a shaft rotatable with said hob shifting means, a cam frictionally supported on said shaft, a switch associated with said cam and arranged to be operated by rotation of the cam, signaling means controlled by said switch and arranged to provide one indication in one position of said cam and a second distinctive indication when said cam has been rotated from said one position, and releasable locking means associated with said cam for preventing rotation of the cam except at the conclusion of a hobbing cycle.

2. A hobbing machine according to claim 1 wherein the means for preventing rotation of the cam comprises a hydraulically actuated plunger adapted to engage the periphery of said cam.

3. A hobbing machine according to claim 1 wherein means are provided for limiting the degree of rotation of the cam from said one position.

4. A hobbing machine in accordance with claim 1 including means for limiting the degree of rota-

tion of the cam from said one position, said cam having a notch formed in the periphery thereof, and a plunger adapted to engage the sides of the notch for returning the cam to said one position.

5. A hobbing machine in accordance with claim 1 wherein means are provided for limiting the degree of rotation of the cam from said one position, said cam having a wedge-shaped notch formed in the periphery thereof, a plunger arranged to enter said notch to prevent rotation of said cam, and means for rotating said shaft independently of the locking action of said plunger with respect to said cam.

6. A hobbing machine in accordance with claim 1 wherein means are provided for adjusting the degree of frictional engagement between said shaft and said cam.

7. A hobbing machine in accordance with claim 1 including a split bushing for supporting said cam on said shaft, and threaded member carried by said cam and arranged to engage the split bushing to adjust the degree of frictional engagement between said shaft and said cam.
